UNITED STATES PATENT OFFICE.

ANNA M. RUEPPEL, OF BUFFALO, NEW YORK.

DESIGN FOR A TOY GARDEN.

Application filed October 13, 1923. Serial No. 7,492. Term of patent 3½ years.

To all whom it may concern:

Be it known that I, ANNA M. RUEPPEL, a citizen of the United States, residing at Buffalo, in the county of Erie and State of New York, have invented a new, original, and ornamental Design for a Toy Garden, of which the following is a specification, reference being had to the accompanying drawing, forming part thereof and in which the figure is a perspective view of the toy garden embodying my new design.

I claim:

The ornamental design for a toy garden, as shown.

ANNA M. RUEPPEL.
